CONTAINER

Alphonse Ouellette, Rosemount, Quebec, Canada,
assignor to Consolidated Lithograph Manufacturing Co. Limited, Montreal, Quebec, Canada

Application September 18, 1936, Serial No. 101,485
In Canada August 22, 1936

1 Claim. (Cl. 229—34)

This invention relates to containers made by creasing and folding a single blank of cardboard or similar flexible material and particularly to containers of this type which are adapted to be expanded to form a display tray or basket for displaying food products and other merchandise.

More particularly, the present invention consists in the provision of a container constructed so that it may be readily converted from a substantially square box-like structure into an octagonal display basket or tray of increased capacity which is useful for displaying fruits, vegetables, and other merchandise.

Proceeding now to a more detailed description reference will be had to the accompanying drawings, wherein—

Fig. 1 is a plan view of the blank from which my improved container is constructed.

Fig. 2 is a view similar to Fig. 1, but showing the blank partly folded.

Fig. 3 is a perspective view of the container produced by appropriate folding of the blank shown in Figs. 1 and 2. In this view one of the auxiliary side wall sections of the container is shown in raised position to disclose parts that would otherwise be hidden from view.

Fig. 4 is a perspective view of the container in partly erected condition.

Fig. 5 is a perspective view showing the complete container as it appears prior to being expanded to form a display tray or basket.

Fig. 6 is a perspective view of the container as it appears in its expanded condition.

Fig. 7 is a sectional view taken substantially along the line 7—7 of Fig. 6.

The blank from which my improved display container is made is shown to advantage in Figs. 1 and 2. This blank is creased to define a square bottom wall 11 having its sides integrally joined to four main side wall sections designated 12 and 13. The sections 12 are hingedly connected to diametrically opposite sides of the bottom wall along suitable crease lines 11a while the sections 13 are similarly connected to the remaining sides of the bottom wall along the crease lines 11b. The main side wall sections 12 are provided with auxiliary side wall sections 12a joined thereto along the crease lines 12b. These auxiliary side wall sections 12a are foldable on the crease lines 12b to overlie the inner sides of the main sections 12 and are provided with extensions 12c adapted to be engaged in slots 12d provided in the bottom wall 11 adjacent the crease lines 11a. The auxiliary side wall sections 12a

are of the same length and width as the main sections 12 to which they are attached.

The main side wall sections 13 are also provided with auxiliary side wall sections 13a joined thereto along the crease lines 13b. The auxiliary side wall sections 13a are foldable on the crease lines 13b to lie against the inner sides of the main sections 13, it being noted that the auxiliary sections 13a are narrower than the main sections 13 but of substantially the same length. 10

Each main side wall section 13 is also provided with integral terminal extensions 14 which are free of attachment to the main side wall sections 12. Each extension 14 is a trapezium figure presenting four angularly related sides designated 14a, 14b, 14c and 14d. The side 14a is hingedly connected to one end of section 13 and lies at right angles to the side 14b which is of equal length. The side 14b is a continuation of that longitudinal edge of section 13 which is hinged to the bottom wall 11 along the crease line 11b. The side 14b thus constitutes the lower edge of the extension 14 and is adapted to rest on the bottom wall 11 when said extension occupies the position shown in Fig. 3. The two remaining sides 14c and 14d of each extension 14 are of equal length with respect to each other but somewhat shorter than the sides 14a and 14b. These sides 14c and 14d are inclined so that, when the wall section 13 is in an upright position, the side 14c slopes downwardly from the horizontal plane containing the upper edge of said section 13 while the side 14d slopes downwardly at a somewhat sharper angle from the lower end of the side 14c to the corner where the side 14d joins the side 14b. It will also be noted that each extension 14 is divided by a diagonal crease line 15 into a pair of foldably related triangular sections 16 and 17. The crease line 15 extends across the extension 14 from the juncture of the sides 14a and 14b to the juncture of the remaining sides 14c and 14d. 35

Each auxiliary side wall section 13a is also provided with terminal extensions 18 of trapezium form defined by the four angularly related side walls 18a, 18b, 18c and 18d. The side 18b is a continuation of the free longitudinal edge 13c of the wall section 13a and forms the lower edge of the extension 18 when the wall sections 13 and 13a are disposed in an upright position with the wall section 13 (see Fig. 4). The side 18a of each extension 18 lies at right angles to the side 18b and is integrally joined to one end of the wall section 13a. The side 18c of each extension 18 is inclined so that it coincides with 50

the side 14c of one of the extensions 14 when the auxiliary wall section 13a is folded to lie against the main section 13. This is shown in Figs. 2, 3, 4 and 6. The remaining side 18d of each section 18 is inclined so that, with the parts arranged as shown in Figs. 2 and 3, it is projected beyond the side 14d of the adjacent extension 14. It will also be noted that each extension 18 is divided by a diagonal crease line 19 into two foldably related sections 20 and 21 of substantially triangular form. When the auxiliary side wall sections 13a are folded to lie against the inner sides of the main sections 13 the crease lines of the extensions 19 coincide 15 with the crease lines 15 of the extensions 14.

In setting up my improved container the auxiliary side wall sections 13 are first folded on the crease lines 13b to lie against the inner sides of the main side wall sections 13. The extensions 18 of the auxiliary wall sections 13 are thus superposed on the extensions 14 of the wall sections 13 as shown to advantage in Fig. 2. In this position of the connected wall sections 13 and 13a the crease lines 19 of the extensions 18 are disposed 25 to coincide with the crease lines 15 of the extensions 14. The wall sections 13 are next bent along the crease lines 11b to the upright position shown in Figs. 3 and 4. The several extensions 14 and 18 are then bent inwardly as shown 30 more particularly in Fig. 4 to lie against the inner surfaces of the side walls 12 which are bent upwardly along the crease lines 11a. The auxiliary side wall sections 12a are then folded downwardly on the crease lines 12b to overlie the adjacent folded extensions 14 and 18 of the side wall sections 13 and 13a. The side wall sections 12a are secured in their downwardly folded position by inserting the tongues 12c in the slots 12d formed in the bottom wall 11. This method of 35 folding the blank results in the production of a square box of the type shown in Fig. 5 but one in which the side wall sections 13 are capable of being swung from the position shown in Fig. 5 to that shown in Figs. 6 and 7. In the latter position the extensions 14 and 18 at each corner of

the container are partially withdrawn from between the adjacent wall sections 12 and 12a to increase the capacity of the container by changing the side wall structure from a square to an octagonal structure. In this connection it will 5 be noted that, with the parts positioned as shown in Fig. 3, there is sufficient clearance above the sloping sides 14c and 18c of the extensions 14 and 18 to permit the triangular sections 16 and 20 of these extensions to move outwardly with the 10 side wall sections 13 and 13a from the position shown in Fig. 3 to that shown in Figs. 6 and 7. It will also be noted that this withdrawal of the corner flap sections 16 and 20 from between the adjacent wall sections 12 and 12a results in the 15 sloping edges 18d of the flap sections 18 being brought into engagement with the folded material joining the upper edges of said sections 12 and 12a so that these edges 18d serve as stops 20 which limit the outward movement of the side wall sections 13 with respect to the ends of the side wall sections 12.

Having thus described my invention what I claim is:

A container of the character described comprising a square bottom wall, side walls extending upwardly from two of the opposite edges of the bottom wall, each of said side walls comprising an outer wall section having its lower edge hinged to the bottom wall and an inner wall 25 section having its upper edge hinged to the outer wall section and its lower edge releasably secured to said bottom wall and two additional side walls hingedly connected to the remaining sides of the bottom wall, each of said additional side walls 30 comprising inner and outer sections provided with integral terminal extensions hingedly connected thereto, said terminal extensions being slidably fitted between the inner and outer wall sections of the first-mentioned side walls and being creased so that portions thereof are capable 35 of assuming an angular position with respect to the first-mentioned side walls when partly withdrawn therefrom.

ALPHONSE OUELLETTE. 45
